UNITED STATES PATENT OFFICE.

FRANK E. HERDMAN, OF WINNETKA, ILLINOIS.

AUTOMATIC REGULATING DEVICE FOR HYDRAULIC ELEVATORS.

SPECIFICATION forming part of Letters Patent No. 635,775, dated October 31, 1898.

Application filed January 23, 1897. Serial No. 620,323. (No model.)

To all whom it may concern:

Be it known that I, FRANK E. HERDMAN, a citizen of the United States, residing at Winnetka, county of Cook, and State of Illinois, have invented a new and useful Improvement in Automatic Regulating Devices for Hydraulic Elevators, of which the following is a full, clear, and exact description, reference being had to the accompanying drawings, which 5 form a part of this specification.

With hydraulic elevators the speed of the car varies according to the load in the car. With one condition of load the full pressure is required to move the car, and as a result 10 a slight friction in the valve and passage is sufficient to produce a slow speed. If the condition of load is such as to require only a light pressure, then the difference of pressure 15 between that required for the load and that 20 at the source of pressure is consumed in overcoming the friction, thereby producing excessive speed. This variation exists also when the elevator or operating cylinder is cut off 25 from the pressure-supply and opened to the outlet.

The object of my invention is to provide a speed-regulator which, governed by the pressure in the elevator or operating cylinder, will control the admission to and discharge from 30 said cylinder, so that a uniform speed with a varying load may be obtained, and to do this without interfering with the control of stopping and starting by the operating-valve.

To that end my invention, broadly considered, consists in combining with the elevator cylinder, having a source of water-supply and an inlet from the source of supply to the cylinder and an outlet from the cylinder, a device 35 adapted to regulate the inflow of water to the cylinder and a regulating device for regulating the out flow of water from the cylinder. Either or both of these two devices may be used and are controlled by a pressure device whose action depends upon the pressure in the operating or elevator cylinder. The regulating device interposed between the elevator-cylinder and the inlet and outlet is independent of the ordinary regulating-valve, which is used 45 to connect the cylinder with the outlet, both the ordinary regulating-valve and this additional regulating device controlling the ad-

mission to and exhaust from the cylinder at the same point.

In the preferred form of embodiment of this invention, broadly considered, I interpose between the cylinder and the inlet or the cylinder and the outlet, or both, a perforated diaphragm, which is partially covered by a shield, which shield is adapted to move upon the diaphragm with reference to the inlet to cut off 55 or cover the diaphragm-perforations at the inlet end or to open them, and the same with reference to the outlet-openings in the diaphragm. This shield is connected with a pressure device controlled by the pressure in 60 the elevator-cylinder, so that the tendency to variations in pressure in the cylinder will move the shield to regulate the inlet or outlet, the operating-valve coacting with the perforated diaphragm on one side and the shield 65 coacting with it on the other side. The preferred form of pressure device that I use is a piston the cylinder of which is connected with the elevator-cylinder, the piston having a spring against which the pressure from the 70 elevator or operating cylinder upon the piston acts. This spring is so regulated that with the proper pressure (to give the desired speed) a given load will not affect or move the piston, and the shield is so formed and is placed in 75 such position upon the perforated diaphragm and connected with the piston that with this condition there will be a proper number of inlet and outlet perforations open to make the 80 proper speed in either ascending or descending with this load, and the variation of load will cause a variation in the movements of the piston through the variation of pressure in the elevator-cylinder and move the shield to cover or uncover the perforations of the 85 diaphragm to regulate the supply or outlet to conform to the changed condition and maintain the speed constant.

I have illustrated my invention as applied to a hydraulic elevator of the plunger type 90 where the weight of the plunger descending lifts the load, the valve to the cylinder being open to discharge under that condition. When the car is descending, this plunger must be lifted, and at such times the operating-valve is moved to open the supply to the 95 cylinder. While my description will be ap-

plied to this plunger type of machine, yet the same mechanism is applicable to all types of hydraulic machinery where different loads are moved, and I desire to have it understood that my invention is not limited to use with any particular type of hydraulic elevators.

In the drawings, Figure 1 is a side elevation of the valve mechanism. Fig. 2 is a section on the line $\alpha\alpha$ of Fig. 1. Fig. 3 is a section on the line $y\gamma$ of Fig. 1. Fig. 4 is a section on the line $w\omega$ of Fig. 3. Fig. 5 is a diagram of the bushing E and the shield II cut and spread on a plane. Fig. 6 is a section on the line $z\zeta$ of Fig. 4. Fig. 7 is a section as on the line $u\eta$ of Fig. 4. Fig. 8 is a side elevation of elevator and attachments.

In the plunger-machine when ascending with a light load there is necessarily a surplus weight in favor of the plunger, and in consequence this surplus weight is taken up, forcing the water out of the cylinder. If the car is heavily loaded in ascending, then the surplus weight is against the plunger, and in consequence there is less force available to force the water out of the cylinder. If under such circumstances the valves and piping were designed to give a proper speed with a heavy load, then with a light load the speed would be excessive unless some mechanism were used to create a resistance to the discharge of the water. The amount of this resistance depends entirely upon the speed desired under these conditions. If the car is descending with a light load, then the valve is open to the supply, and if the pipes are designed for the proper speed under such circumstances it would require the full pressure of the supply to give this speed, as the excessive weight of the plunger has to be lifted, while if the car is descending with a heavy load there is much less weight of the plunger to be lifted, and in consequence less pressure required to lift the plunger. As a result the difference of this pressure and the pressure of the supply would give a great velocity to the flow of the water and corresponding excessive speed to the plunger under these conditions. If the car is ascending with a light load and the discharge-port is sufficiently choked, the speed can be limited to the desired amount, and when descending with a heavy load if the supply-port is properly choked the speed can be limited to the desired amount. The difficulty in choking such ports is that it is likely to give a short choppy movement to the valve, which gives a sudden stop to the car. The automatic devices hereinafter described are arranged so that while they choke the inlet and outlet ports still they do not in any way interfere with the graduated cut-off of the operating-valve, its action on the speed being throughout its full travel the same as before.

A is the inlet or supply port connecting through the operating-valve chamber B' and mechanism to be hereinafter described with the elevator or operating cylinder C.

B is the operating-valve in chamber B'. D is the outlet-port.

b b' are the valve-heads on the valve B. (Shown in Fig. 3 at the central position.) This valve is controlled and moved by means of the piston-heads b^2 b^3 , which are brought in connection with water or fluid through the medium of the valve D', having the inlet-port d and the passage d' leading to the operating-valve chamber of the valve B on the head side b^2 , while the passage d^2 leads to the other side—to wit, the head b^3 —while the passage d^3 leads to the exhaust D. This valve D' is under the control of the operator, and by moving it the connection may be made between the cylinder and either the inlet or discharge port.

The valve B works in the bushing E, which has perforations in it at the enlargement of the casing E, where the passage c leads to the operating-cylinder C. These perforations are shown in Fig. 5 and are such that as the valve-piston cuts off port c from its connection with A or D it does so gradually, cutting the greater amount off at the start, and as it nears the final cut-off doing so gradually to prevent any noticeable shock in the car.

G G are two rings connected together and threaded on the inside. In each ring is placed a sleeve or jacket H. (Shown in detail, Fig. 5.) These sleeves or jackets H are adjustable in the rings G G and are held from slipping by set-screws g and are curved to conform to the graduation of the perforations, being, like the perforations, brought up to a point. From this construction when either sleeve or jacket is moved to choke the perforations at its end it does so on all sides at once, with the exception of the apex of the perforations, which it will only partially interfere with. Such being the case, if either sleeve is thrown over the perforations at its end it leaves the remaining perforations so graduated that the operating-valve piston has to have its full travel to fully cut off the water, and so that the operating-valve in moving to admit or cut off the water will always solely control a portion of the inlet, so that it will be able to cut off for a stop without delay and gradually. The rings G G are carried by a rocker I, connected with a lever J on the outside of the valve. The lever J is connected with the piston-rod K in the cylinder L. The cylinder L is connected with the elevator-cylinder C by the pipe M. In the cylinder L is the spring L', opposing the action of the pressure from cylinder C.

The operating-valve has a movement so that either port A or port D is brought into connection with port c, leading to elevator-cylinder C, the valve being shown in Fig. 3 in a horizontal position. The operating-valve has a movement so that port A or port D is connected with the port C through half only of the perforations. The spring L' is of strength sufficient to prevent the movement of the piston-rod K with the minimum desired pressure

in the elevator or operating cylinder. The plates or jackets are arranged in such position, as shown, to leave open the proper number of perforations in the inlet and exhaust portion of the jacket. Under these conditions—that is, the passage of the supply to the cylinder when the operating-valve is open would be choked while in this position if the valve were turned to connect with the exhaust or discharge—the fullest number of perforations corresponding to the exhaust would be opened. If under these conditions, say, the elevator is ascending with a heavy load, the weight on the side of the plunger overbalancing the elevator would be at a minimum, and in consequence the least amount of weight would be used in forcing the water out of the discharge. In such case the discharge should be perfectly free. If, on the other hand, the car is going down with a full load, the excessive weight on the side of the plunger would be still at a minimum, and in consequence a small amount of pressure would be required to lift the plunger. Such being the case, the supply-port should be choked to prevent excessive speed. These conditions exist as shown in Figs. 3, 4, and 5. If ascending with a light load, then the excessive weight on the side of the plunger would tend to force the water out of the cylinder with great velocity. The excessive weight of plunger produces an excessive back pressure in the cylinder, and this back pressure necessarily compresses the spring L' and moves the lever J, so as to cause the shield H to choke the perforations between the port D and C, thereby producing an extreme resistance to this discharge and preventing an excessive speed. On the other hand, if descending with a light load this excessive weight on the side of the plunger will have to be lifted, requiring the full water-pressure to do so. Such being the case, a free passage of the water through the supply would be necessary to give the proper speed. Under such conditions of load the full pressure would be felt in the cylinder, and in consequence the spring L' would be compressed to that amount. Such compression would move the shield H, so as to give the full opening of the perforations between the supply-port A and the operating-cylinder. This meets the desired conditions in this respect. All other conditions of load are between these two, and the perforations should be proportionately opened or closed, and this would necessarily be produced by the pressure in the cylinder acting on the spring L'.

In Fig. 8 I have shown the device shown in the other figures connected with the elevator-cylinder, the car, and its appurtenant mechanism. In this drawing, C is the operating-cylinder, in which works the plunger N', on the top of which are the weights N''. O is the traveling sheave carried by and moving with the plunger. The lifting-cable P is attached at one end to the fixed point p, passes around the traveling sheave O, thence over the

sheave O' O'' to the elevator-car Q. R is the operating-cable, which passes around the sheaves r r', through the car around the sheave r'', at the bottom around the sheave r''', which is connected with the rock-shaft r''', which rock-shaft is in connection with the operating-valve D'.

As may be seen from the foregoing, in elevating mechanism constructed so as to embody my invention the flow of water to and from the elevator-cylinder is regulated dependent upon the pressure in the elevator-cylinder itself, so that the flow to and from conforms to the requirements. Further, this is accomplished without in any way detracting from the operation and effect of the ordinary operating-valve.

The operating-valve of a hydraulic elevator is an important piece of mechanism, particularly where the elevator is a high-speed elevator. This valve must be adjusted so as to cut off the flow of water gradually, or otherwise under certain conditions the effect upon the car would be injurious and disagreeable to the passengers in the car. Thus if the valve is shut off quickly or suddenly with the high-speed elevator there would be a tendency for the car to jerk or jump, which is very objectionable. When ascending light, with the valve wide open, the water would be forced through the discharge with great velocity due to the weight of the unbalanced plunger, and the car would have great speed. The valve must be adjusted for this extreme, so that when stopping there shall be no jump or jerk—that is, it must be adjusted to cut off gradually. As a reverse case, when ascending with a heavy load with the same adjustment the movement of the valve when stopping will be liable to be too slow. For this reason it is very desirable to use mechanism which will regulate the flow of the water to and from the elevator dependent upon the weight in the car, and thus maintain a substantially constant speed of travel for the car. This being accomplished with one adjustment of operating-valve, or rather one adjustment of the graduations of cutting off the supply of water, the valve will operate with any weight of car, as the car always maintaining substantially the same speed independent of the load one adjustment for the stop will be an adjustment for all conditions. Where this pressure-regulating device is placed in the pipe or connection leading from the operating-valve to the elevator-cylinder at a point beyond the control of the operating-valve, while the inlet and discharge of the water from the cylinder is regulated by the weight of the car, still the operation of the operating-valve becomes defective for the following reason: While the pressure device does control the flow of water to and from the elevator-cylinder beyond the point where it is placed, still the operating-valve has full control of the water up to that point, and as a consequence if the operating-valve be

thrown fully open the water will pass to this pipe or connection without any restriction. Under these conditions if the operator desires to stop before any effect can be obtained from the movement of the operating-valve it is necessary for it to move a distance sufficient to close the inlet or connection at the point where the operating-valve is placed an amount equal to the extent of closure at the point where the regulating device is placed. Therefore under these conditions before the elevator can commence to stop the operating-valve has to move over this distance, and therefore will have to do all its action to cut off in the short space left, and to do this will give such a slow travel to the valve in its whole travel that the operator has not good control of the car. Practically the operation is through the pressure-regulating device to contract the connection to the elevator-cylinder at its opening into the valve-chest proportionately throughout its entire extent, thus, as it were, contracting the part controlled by the valve throughout the entire length of travel of the valve, contracting it proportionately throughout the entire length. In consequence at all times the operating-valve has immediate and prompt effect on the action of the car, and it responds at once. If this opening is choked or contracted greatly to prevent excessive speed, it is done proportionately throughout the entire movement of the valve, and in consequence as soon as the valve commences to close the car commences to respond. This gives the operator perfect control of the elevator and much more rapid movement of the valve. Speaking generally, it may be seen that the apparatus operates to accomplish this by reason of having an inlet from the source of water-supply to the cylinder, an operating-valve adapted to open and close said inlet, a regulating-valve adapted to vary the size of said inlet, and a pressure device controlled by the pressure in the elevator-cylinder, and connection between the pressure device and the regulating-valve, whereby the action of the regulating device is controlled by the pressure in the elevator-cylinder. This may be stated to be the idea in its broadest sense, with the understanding that of course it is equally applicable to the outlet from the cylinder to the discharge. More narrowly, it consists in controlling the connection between the operating-valve cylinder or casing and the elevator-cylinder by means of both an operating-valve and a regulating device, the movement of the regulating device being controlled by the pressure in the elevator-cylinder, both the operating-valve and the regulating device acting to regulate the size of the connection between the valve cylinder or case and the elevator-cylinder, there being, however, a portion of said connection which is controlled entirely by the valve from its initial movement to its ultimate position. It may further be expressed by the same construction of parts where they both move in opposite directions

to close and open this connection. Thus the operating-valve and the regulating device are always ready to respond at once to their full capacity. It further may be expressed by the fact that the operating-valve and the regulating device move to contract the connection at an angle to each other. 70

Having now fully described my invention, 75 what I claim, and desire to protect by Letters Patent, is—

1. In a hydraulic elevator, in combination, an elevator-cylinder, a source of water-supply, an inlet from the source of water-supply to the cylinder, an outlet from the cylinder, an operating-valve adapted to control said inlet and outlet, a regulating device interposed between the cylinder and the inlet and outlet and adapted to regulate the inlet to and outlet from the cylinder, a pressure device controlled by the pressure in the cylinder, and connection between said pressure device and the regulating device whereby the action of said last-mentioned device is controlled by 90 the pressure in the cylinder. 85

2. In a hydraulic elevator, in combination, an elevator-cylinder, a source of water-supply, an inlet from the source of water-supply to the cylinder, an outlet from the cylinder, a regulating device interposed between the cylinder and the inlet and outlet and adapted to regulate the inlet to and outlet from the cylinder, a spring or weighted piston the cylinder of which is in connection with the elevator-cylinder, and connection between said inlet and outlet water-regulating device and said piston whereby the movement of said piston controls the movement of said regulating device. 95 100 105

3. In a hydraulic elevator, in combination, an elevator-cylinder, a source of water-supply, an inlet from the source of water-supply to the cylinder, an outlet from the cylinder, a regulating device interposed between the cylinder and the inlet and outlet and adapted to regulate the inlet to and exhaust from the cylinder, a pressure device controlled by the pressure in the cylinder, and connection between said pressure device and the regulating device whereby the action of said last-mentioned device is controlled by the pressure in the cylinder, an operating-valve operating independently of the regulating device, and means independent of the regulating-device-controlling mechanism, to control said operating-valve. 110 115 120

4. In a hydraulic elevator, in combination, an elevator-cylinder, a source of water-supply, an inlet from the source of water-supply to the cylinder, an outlet from the cylinder, a regulating device interposed between the cylinder and the inlet and outlet and adapted to regulate the inlet to and outlet from the cylinder, a spring or weighted piston the cylinder of which is in connection with the elevator-cylinder, connection between said regulating device and said piston whereby the movement of said piston controls the move- 125 130

ment of said regulating device, an operating-valve operating independently of the regulating device, and means independent of the regulating-device-controlling mechanism, to control said operating-valve.

5. In a hydraulic elevator, in combination, an elevator-cylinder, a source of water-supply, an inlet from the source of water-supply to the cylinder, an outlet from the cylinder, a regulating device interposed between the cylinder and the inlet and outlet adapted in its movement to cut off and open gradually the inlet to and exhaust from the cylinder but not to close said inlet and outlet completely, a pressure device directly controlled by the pressure in the cylinder, and connection between said pressure device and the regulating device whereby the action of said last-mentioned device is controlled by the pressure in the cylinder.

6. In a hydraulic elevator, in combination, an elevator-cylinder, a source of water-supply, an inlet from the source of water-supply to the cylinder, a diaphragm having at different points varying opening capacity interposed between the elevator-cylinder and inlet, a shield controlling said openings but of such size as at no time to cover all of said openings, a pressure-regulating device controlled by the pressure in the elevator-cylinder, and connection between said pressure device and the shield whereby the action of the shield is controlled by said pressure device.

7. In a hydraulic elevator, in combination, an elevator-cylinder, a source of water-supply, an inlet from the source of water-supply to the cylinder, and an outlet from the cylinder, a diaphragm having at different points varying opening capacity interposed between the elevator-cylinder and inlet and outlet, a shield controlling said openings but of such size as at no time to cover all of said openings, a pressure-regulating device controlled by the pressure in the cylinder, and connection between said shield and the pressure-regulating device whereby said pressure-regulating device controls the movement of said shield.

8. In a hydraulic elevator, in combination, an elevator-cylinder, a source of water-supply, an outlet from the elevator-cylinder, a diaphragm having at different points varying opening capacity interposed between the elevator-cylinder and outlet, a shield controlling said openings but of such size as at no time to cover all of said openings, a pressure-regulating device controlled by the pressure in the elevator-cylinder, and connection between said pressure device and the shield whereby the action of the shield is controlled by said pressure device.

9. In a hydraulic elevator, in combination, an elevator-cylinder, a source of water-supply, an inlet from the source of water-supply to the cylinder, a diaphragm having gradually-decreasing opening capacity at different points interposed between the elevator-cylinder and inlet, a shield controlling said open-

ings but of such size as at no time to cover all of said openings, a pressure-regulating device controlled by the pressure in the elevator-cylinder, and connection between said pressure device and the shield whereby the action of the shield is controlled by said pressure device.

10. In a hydraulic elevator, in combination, an elevator-cylinder, a source of water-supply, an inlet from the source of water-supply to the cylinder, and an outlet from the cylinder, a diaphragm having gradually-decreasing opening capacity at different points interposed between the elevator-cylinder and inlet and outlet, a shield controlling said openings but of such size as at no time to cover all of said openings, a pressure-regulating device controlled by the pressure in the cylinder, and connection between said shield and the pressure-regulating device whereby said pressure-regulating device controls the movement of said shield.

11. In a hydraulic elevator, in combination, an elevator-cylinder, a source of water-supply, an outlet from the elevator-cylinder, a diaphragm having gradually-decreasing opening capacity at different points, interposed between the elevator-cylinder and outlet, a shield controlling said openings but of such size as at no time to cover all of said openings, a pressure-regulating device controlled by the pressure in the elevator-cylinder, and connection between said pressure device and the shield whereby the action of the shield is controlled by said pressure device.

12. In a hydraulic elevator, in combination, an elevator-cylinder, a source of water-supply, an inlet from the source of water-supply to the cylinder, a diaphragm having perforations arranged in tapering form interposed between the elevator-cylinder and inlet, a tapered shield controlling said perforations but of such size as at no time to cover all of said perforations, a pressure-regulating device controlled by the pressure in the elevator-cylinder, and connection between said pressure device and the shield whereby the action of the shield is controlled by said pressure device.

13. In a hydraulic elevator, in combination, an elevator-cylinder, a source of water-supply, an inlet from the source of water-supply to the cylinder, and an outlet from the cylinder, a diaphragm having perforations arranged in tapering form interposed between the elevator-cylinder and inlet and outlet, a tapered shield controlling said perforations but of such size as at no time to cover all of said perforations, a pressure-regulating device controlled by the pressure in the cylinder, and connection between said shield and the pressure-regulating device whereby said pressure-regulating device controls the movement of said shield.

14. In a hydraulic elevator, in combination, an elevator-cylinder, a source of water-supply, an outlet from the elevator-cylinder,

- a diaphragm having perforations arranged in tapering form interposed between the elevator-cylinder and outlet, a tapered shield controlling said perforations but of such size as 5 at no time to cover all of said perforations, a pressure-regulating device controlled by the pressure in the elevator-cylinder, and connection between said pressure device and the shield whereby the action of the shield is controlled by said pressure device.
15. In a hydraulic elevator, in combination, an elevator-cylinder, a source of water-supply, an inlet from the source of water-supply to the cylinder, an outlet from the cylinder, a diaphragm having openings interposed between the inlet to and outlet from the cylinder, and a shield adapted in its movements to cover and uncover the openings in said diaphragm, a pressure device directly controlled 15 by the pressure in the elevator-cylinder, and connection between said pressure device and said shield whereby the movement of said shield is controlled by the pressure device.
16. In a hydraulic elevator, in combination, an elevator-cylinder, a source of water-supply, an inlet from the source of water-supply to the cylinder, an outlet from the cylinder, an operating-valve, a diaphragm having 20 openings placed in the operating-valve, and a shield adapted in its movements to cover and uncover the openings in said diaphragm, a spring or weighted piston, the cylinder of which is in direct connection with the elevator-cylinder, and connection between said shield and said piston whereby the movement of said piston controls the movement of said regulating device.
17. In a hydraulic elevator, in combination, an elevator-cylinder, a source of water-supply, an inlet from the source of water-supply to the cylinder, an outlet from the cylinder, an operating-valve, a diaphragm having 25 openings placed in the operating-valve, and a shield adapted in its movements to cover and uncover the openings in said diaphragm, a spring or weighted piston the cylinder of which is in connection with the elevator-cylinder, and connection between said shield and said piston whereby the movement of said piston 30 controls the movement of said regulating device.
18. In a hydraulic elevator, in combination, an elevator-cylinder, a source of water-supply, an inlet from the source of water-supply to the cylinder, an operating-valve, a cylinder having openings placed in the valve, a shield on the exterior of the cylinder adapted in its movement to cover and uncover said openings, a pressure-regulating device controlled by the pressure in the elevator-cylinder, and connection between said pressure device and the shield whereby the action of the shield is controlled by said pressure device.
19. In a hydraulic elevator, in combination, an elevator-cylinder, a source of water-supply, an inlet from the source of water-supply to the cylinder, an outlet from the ele- 55 vator-cylinder, a cylinder interposed between the elevator-cylinder and the inlet and outlet, said cylinder having openings opposite the inlet and outlet, a shield having a cut-away central portion and adapted in its movement in one direction to move over the inlet-perforations and uncover the outlet-openings, and vice versa in the other direction, a pressure-regulating device controlled by the pressure in the cylinder, and connection between said shield and the pressure-regulating device controls the movement of said shield.
20. In a hydraulic elevator, in combination, an elevator-cylinder, a source of water-supply, an inlet from the source of water-supply to the elevator-cylinder, and an outlet from said cylinder, a diaphragm interposed 60 between the cylinder and inlet and outlet, said diaphragm having perforations corresponding to the elevator-cylinder inlet and outlet, a shield for said diaphragm, adapted in its movement in one direction to cover the outlet-openings and uncover the inlet, and vice versa in the other direction, a pressure-regulating device operated by the pressure in the elevator-cylinder, and connection between the pressure-regulating device and the shield whereby the movement of the shield is controlled by the pressure-regulating device.
21. In a hydraulic elevator, in combination, an elevator-cylinder, a source of water-supply, an inlet from the source of water-supply to the cylinder, an outlet from the elevator-cylinder, a cylinder interposed between the elevator-cylinder and the inlet and outlet, said cylinder having perforations opposite the inlet and outlet, a shield having a cut-away central portion and adapted in its movement in one direction to move over the inlet-perforations and uncover the outlet-openings, and vice versa in the other direction, a spring or weighted piston, a cylinder in which said piston works, said cylinder being in connection with the elevator-cylinder, and connection between said shield and said piston, whereby the movement of said piston controls the movement of said shield.
22. In a hydraulic elevator, in combination, an elevator-cylinder, a source of water-supply, an inlet from the source of water-supply to the elevator-cylinder, and an outlet from said cylinder, a diaphragm interposed 70 between the cylinder and inlet and outlet, said diaphragm having openings corresponding to the elevator-cylinder inlet and outlet, a shield for said diaphragm, adapted in its movement in one direction to cover the outlet-openings and uncover the inlet, and vice versa in the other direction, a spring or weighted piston, a cylinder in which said piston works, said cylinder being in connection with the elevator-cylinder and connection between said shield and said piston whereby the movement of said piston controls the movement of said shield.
23. In a hydraulic elevator, in combina- 75

tion, an elevator-cylinder, a port in connection with the cylinder, an operating-valve adapted to open and close said port, a regulating device adapted to vary the size of said port, a pressure device controlled by the pressure in the elevator-cylinder, and connection between the pressure device and the regulating device, whereby the action of the regulating device is controlled by the pressure in the elevator-cylinder.

24. In a hydraulic elevator, in combination, an elevator-cylinder, a port in connection with the cylinder, an operating-valve adapted to open and close said port, a regulating device adapted to open and close a portion only of said port, another portion of said port being controlled solely by said operating-valve from its initial to its ultimate position, a pressure device controlled by the pressure in the elevator-cylinder, and connection between the pressure device and the regulating device, whereby the action of the regulating device is controlled by the pressure in the elevator-cylinder.

25. In a hydraulic elevator, in combination, an elevator-cylinder, a port in connection with said cylinder, an operating-valve adapted in its movement to open and close said port, a regulating device adapted to move in opposite directions respectively to the operating-valve to partially open and close said port, a pressure device controlled by the pressure in the elevator-cylinder, and connection between the pressure device and the regulating device whereby the action of the regulating device is controlled by the pressure in the elevator-cylinder.

26. In a hydraulic elevator, in combination, an elevator-cylinder, a port in connection with said cylinder, an operating-valve adapted by its movement in opposite directions to open and close said port, a regulating device adapted to partially open and close said port, the operating-valve moving in one direction and the regulating-valve in an opposite direction to close said port, a pressure device controlled by the pressure in the elevator-cylinder, and connection between the pressure device and the regulating device, whereby the action of the regulating device is controlled by the pressure in the elevator-cylinder.

27. In a hydraulic elevator, in combination, an elevator-cylinder, a source of water-supply, an inlet-port from the source of water-supply to the cylinder, an outlet-port from the cylinder, an operating-valve adapted to open and close said inlet and outlet ports, a regulating device adapted to vary the size of said inlet and outlet ports, a pressure device controlled by the pressure in the cylinder, and connection between said pressure device and the regulating device whereby the action of the regulating device is controlled by the pressure in the cylinder.

28. In a hydraulic elevator, in combination, an elevator-cylinder, a source of water-

supply, an inlet from the source of water-supply to the cylinder, an outlet from the cylinder, operating-valves adapted to open and close said inlet and outlet, a regulating device adapted to open and close a portion of said inlet and outlet, the other portion of said inlet and outlet being controlled solely by said operating-valve from its central to its opposite ultimate positions respectively, a pressure device controlled by the pressure in the cylinder, and connection between said pressure device and the regulating device whereby the action of the regulating device is controlled by the pressure in the cylinder.

29. In a hydraulic elevator, in combination, an elevator-cylinder, a source of water-supply, an inlet from the source of water-supply to the cylinder, an outlet from the cylinder, an operating-valve adapted in its movement from its center in one direction to open the inlet, and vice versa, and in its movement from its center in the other direction to open the outlet and vice versa, a regulating device adapted to move in opposite directions respectively to the operating-valve to partially open and close said inlet and outlet, a pressure device controlled by the pressure in the cylinder, and connection between said pressure device and the regulating device whereby the action of the regulating device is controlled by the pressure in the cylinder.

30. In a hydraulic elevator, in combination, an elevator-cylinder, a source of water-supply, an inlet from the source of water-supply to the cylinder, an outlet from the cylinder, an operating-valve adapted by its movement in opposite directions on either side of its central position to open and close said inlet and outlet, a regulating device adapted to partially open and close said inlet and outlet at an angle to the direction in which said inlet and outlet is opened and closed by the movement of the operating-valve, a pressure device controlled by the pressure in the cylinder, and connection between said pressure device and the regulating device whereby the action of the regulating device is controlled by the pressure in the cylinder.

31. In a hydraulic elevator, in combination, an elevator-cylinder, a port in connection with the cylinder, an operating-valve adapted to open and close said port, a regulating device adapted to vary the size of said port, a spring or weighted piston, a cylinder containing the same which is in constant connection with the elevator-cylinder, and connection between the regulating device and said piston whereby the movement of said piston controls the movement of said regulating device.

32. In a hydraulic elevator, in combination, an elevator-cylinder, an inlet from the source of water-supply to the cylinder, an outlet from the cylinder, an operating-valve adapted to open and close said inlet and out-

- let, a regulating device interposed between the cylinder and the inlet and outlet and adapted to vary the size of said inlet and outlet, a spring or weighted piston, a cylinder containing the same which is in constant connection with the elevator-cylinder, and connection between the regulating device and said piston whereby the movement of said piston controls the movement of said regulating device.
33. In a hydraulic elevator, in combination, an elevator-cylinder, a port in connection with the cylinder, an operating-valve adapted to open and close said port, a regulating device adapted to vary the size of said port, a pressure device controlled by the pressure in the elevator-cylinder, and connection between the pressure device and the regulating device whereby the action of the regulating device is controlled by the pressure in the elevator-cylinder, and means independent of the regulating-device-controlling mechanism to control said operating-valve.
34. In a hydraulic elevator, in combination, an elevator-cylinder, a source of water-supply, an inlet from the source of water-supply to the cylinder, an outlet from the cylinder, an operating-valve adapted to open and close said inlet and outlet, a regulating device interposed between the cylinder and the inlet and outlet and adapted to vary the size of said inlet and outlet, a pressure device controlled by the pressure in the cylinder, and connection between said pressure device and the regulating device whereby the action of the regulating device is controlled by the pressure in the cylinder, and means independent of the regulating-device-controlling mechanism to control said operating-valve.
35. In a hydraulic elevator, in combination, an elevator-cylinder, a port in connection with the cylinder, an operating-valve adapted to open and close said port, a regulating device adapted to vary the size of said port, a spring or weighted piston, a cylinder containing the same which is in constant connection with the elevator-cylinder, and connection between the regulating device and said piston whereby the movement of said piston controls the movement of said regulating device, and means independent of the regulating-device-controlling mechanism to control said operating-valve.
36. In a hydraulic elevator, in combination, an elevator-cylinder, an inlet-port from the source of water-supply to the cylinder, an outlet-port from the cylinder, an operating-valve adapted to open and close said inlet and outlet ports, a regulating device adapted to vary the size of said inlet and outlet ports, a spring or weighted piston, a cylinder containing the same which is in constant connection with the elevator-cylinder, and connection between the regulating device and said piston whereby the movement of said piston controls the movement of said regulating device, and

means independent of the regulating-device-controlling mechanism to control said operating-valve.

37. In a hydraulic elevator, in combination, an elevator-cylinder, a passage in connection with the cylinder, a perforated diaphragm interposed in said passage, an operating-valve adapted to move along said diaphragm to open and close said passage, a shield adapted in its movements to cover and uncover perforations in said diaphragm, a pressure device directly controlled by the pressure in the elevator-cylinder, and connection between the pressure device and said shield, whereby the movement of said shield is controlled by the pressure in the elevator-cylinder.

38. In a hydraulic elevator, in combination, an elevator-cylinder, a source of water-supply, an inlet from the source of water-supply to the cylinder, an outlet from said cylinder, a perforated diaphragm interposed between the cylinder and said inlet and outlet, an operating-valve adapted to move along said diaphragm to open and close said inlet and outlet, a shield adapted in its movements to cover and uncover perforations in said diaphragm, a pressure device directly controlled by the pressure in the elevator-cylinder, and connection between the pressure device and said shield, whereby the movement of said shield is controlled by the pressure in the elevator-cylinder.

39. In a hydraulic elevator, in combination, an elevator-cylinder, a passage in connection with said cylinder, a cylinder having perforations interposed in said passage, a shield on the exterior of the cylinder adapted in its movement to cover and uncover said perforations, an operating-valve adapted to move back and forth within said cylinder and thus open and close said passage, a pressure device controlled by the pressure in the elevator-cylinder, and connection between the pressure device and the shield whereby the action of the shield is controlled by said pressure device.

40. In a hydraulic elevator, in combination, an elevator-cylinder, a source of water-supply, an inlet from the source of water-supply to the cylinder, an outlet from said cylinder, a cylinder having perforations interposed between the elevator-cylinder and the inlet and outlet, a shield on the exterior of the cylinder adapted in its movement to cover and uncover said perforations, an operating-valve adapted to move back and forth within said cylinder and thus open and close said inlet and outlet, a pressure device controlled by the pressure in the elevator-cylinder, and connection between the pressure device and the shield whereby the action of the shield is controlled by said pressure device.

41. In a hydraulic elevator, in combination, an elevator-cylinder, a passage in connection with the cylinder, a cylinder having perforations interposed in said passage, a shield on the exterior of the cylinder adapted

in its movement to cover and uncover said perforations, an operating-valve adapted to move back and forth within said cylinder and thus open and close said passage, a spring or weighted piston, a cylinder containing the same which is in direct connection with the elevator-cylinder, and connection between the shield and said piston whereby the movement of said piston controls the movement of said shield.

42. In a hydraulic elevator, in combination, an elevator-cylinder, a source of water-supply, an inlet from the source of water-supply to the cylinder, an outlet from said cylinder, a cylinder having perforations interposed between the elevator-cylinder and the inlet and outlet, a shield on the exterior of the cylinder adapted in its movement to cover and uncover said perforations, an operating-valve adapted to move back and forth within said cylinder and thus open and close said inlet and outlet, a spring or weighted piston, a cylinder containing same which is in direct connection with the elevator-cylinder, and connection between the shield and said piston whereby the movement of said piston controls the movement of said shield.

43. In a hydraulic elevator, in combination, an elevator-cylinder, a port in connection with said cylinder, an operating-valve adapted by its movement in opposite directions to open and close said port, a regulating device adapted to partially open and close said port, the operating-valve moving in one direction and the regulating-valve in a different direction to close said port, a pressure device controlled by the pressure in the eleva-

tor-cylinder, and connection between the pressure device and the regulating device whereby the action of the regulating device is controlled by the pressure in the elevator-cylinder.

44. In a hydraulic elevator, in combination, an elevator-cylinder, a source of water-supply, an inlet from the source of water-supply to the cylinder, an outlet from the cylinder, a regulating device interposed between the cylinder and the inlet and outlet and adapted to regulate the inlet to and outlet from the cylinder, a pressure device controlled by the pressure in the cylinder, and connection between said pressure device and the regulating device whereby the action of said last-mentioned device is controlled by the pressure in the cylinder.

45. In a hydraulic elevator, the combination with a car, a cylinder, a supply and exhaust port for said cylinder, an operating-valve and a speed-governor valve both controlling said port, of manual devices connected with said car and operating said operating-valve, a pressure device controlled by the pressure in the elevator-cylinder, and connection between the pressure device and the speed-governor valve, whereby the action of the latter is controlled by the pressure in the elevator-cylinder.

In testimony of which invention I have hereunto set my hand.

FRANK E. HERDMAN.
